UNITED STATES PATENT OFFICE.

LOUIS GODDU, OF WINCHESTER, MASSACHUSETTS, ASSIGNOR TO THE
GODDU IMPROVEMENT COMPANY OF MAINE.

SAFETY DEVICE FOR CABLE ROADS.

SPECIFICATION forming part of Letters Patent No. 349,344, dated September 21, 1886.

Application filed March 1, 1886. Serial No. 193,552. (No model.)

To all whom it may concern:

Be it known that I, LOUIS GODDU, of Winchester, county of Middlesex, and State of Massachusetts, have invented an Improvement in 5 Safety Devices for Cable Roads, of which the following description, in connection with the accompanying drawings, is a specification, like letters on the drawings representing like parts.

This invention relates to cable railways, and 10 has for its object to provide the same with a safety stopping device to be used in conjunction with or without the means now commonly employed to stop the motion of the car, and is especially adapted to be used on that part 15 of the road where the travel of teams and other similar vehicles does not occur and on heavy grades.

My invention consists of one or more cables supported above and distributed as desired 20 in the direction of the length of the road-bed, combined with one or more sheaves supported below the car and adapted to pass under said cable, and with a gripping device to clamp the cable, to thereby stop the motion of the car.

25 My invention also consists of one or more cables supported above and distributed as desired in the direction of the length of the road-bed, combined with one or more sheaves supported below the car and adapted to pass under said cable, and with a gripping device to clamp the cable to said sheave, to thereby stop the motion of the car.

Cable railways as now constructed are wanting in additional means to insure the stopping 35 of the car, if for any reason the usual brake or gripping device should become inoperative.

Figure 1 shows in elevation a car and a sufficient portion of a railway to enable my invention to be understood; Fig. 2, a plan view of 40 Fig. 1, with the car removed, and with the support for the sheaves in section; Fig. 3, an enlarged detail of the gripping mechanism; and Fig. 4, a section on line $x-x$, Fig. 3, looking down.

45 In order that my invention may be clearly understood, I have shown in Fig. 1 a car, A, of any ordinary construction, and such as commonly used on cable roads, provided with an arm, a , attached to the bottom of said car by bolts a' , the said car being adapted to be moved, in the usual manner, by a cable carried below

the road-bed B, and not herein shown, the said car also having the usual gripping device used in connection with the cable located below the road-bed, and by which to place the car in motion, said gripping device not being herein shown, as it forms no part of the present invention.

In accordance with my invention I purpose to secure by spikes b , or otherwise, at suitable 60 intervals along the road-bed B, and especially on ascending and descending grades, preferably metal plates b' , each of which is provided with a bent arm, b^3 , and I further purpose to secure to each of said bent arms one end of a 65 cable, c , there being a cable extended between every pair of plates, as shown in the drawings. The bent arm b^3 of each plate is of the requisite height to permit a sheave or roller, d , carried by the arm a , attached to the bottom 70 of the car, to pass beneath it, and to engage the cable c when said car is moved past said bent arms, said cable resting upon the said sheave or roller d , as shown in Fig. 1.

If for any reason—such as the slipping on 75 the cable of the usual apparatus or gripping devices for moving the car—it is desired to stop the car, the engineer operates a gripping device from within the car to grip the cable c . The gripping device herein shown is composed 80 of a fixed jaw, e^2 , and a movable jaw, e^3 . The jaw e^2 is herein shown as cast integral with the supporting-arm a , and is provided with a slot, e' , in which is located a sheave or roller, d , having for its axis the pin d' . The movable 85 jaw has a stud or bolt, e^4 , which is extended through a slot, e^5 , in the arm a , said bolt being adapted to slide in the slot e^5 , and being provided with a nut, e^6 , to keep the jaw e^3 in place. The jaw e^3 has an ear, to which is secured one end of a link, f' , the other end of 90 said link being pivoted, as at f^2 , to an arm, f^3 , of an elbow or hand-lever pivoted at f^4 , the long arm f^5 of said lever extending up into the interior of the car, and being provided with 95 a handle, f^6 . The arm a is of such length as to permit the jaw e^2 to pass under the bent arms b^3 as the car is moved in usual manner past said arms. As the jaw e^2 is moved past the bent arms b^3 , it also engages the cable c , 100 which rides upon and over said jaw and roller d , carried thereby, as shown in Fig. 1.

When it is desired to stop the car in case of an accident, or for other like cause, the engineer or driver in the car pushes the arm f^e from its dotted-line position in Fig. 3 in the direction of arrow 2, and as the arm f^e is moved from its dotted-line position in the direction of arrow 2 the upper jaw, e^e , is moved down until it grips the cable c between it and the lower jaw. The upper jaw is concaved near its center to receive the roller or sheave d , and the cable c is gripped between the said upper and lower jaw and between the upper jaw and the roller d .

To enable the jaws to more securely bite or grip the cable, I have herein shown the said jaws, and also the roller or sheave, as provided with corrugations, which correspond to and fit the strands of the cable.

In Fig. 2 I have shown a series of blocks, h' , distributed at intervals along the road-bed between the bent arm b^e , upon which it is designed the cable c should rest; but, if desired, said blocks may be omitted, and the cable rest directly upon the road-bed.

I have herein shown one form of gripping device or jaw by which to clutch the cable; but it is evident that other usual forms of gripping devices or jaws might be used in combination with the cable c .

I do not desire to limit myself to the use of a cable just such as shown, as it is evident other equivalent means supported above the road-bed may be employed.

I claim—

1. In a cable railway, one or more fixed or stationary cables supported above and distributed as desired in the direction of the length of the road-bed, combined with one or more sheaves supported below the car and adapted to pass under said cable, and with a gripping device to clamp the cable, to thereby stop the motion of the car, substantially as described.

2. In a cable railway, one or more fixed or stationary cables supported above and distributed as desired in the direction of the length of the road-bed, combined with one or more sheaves, and with a gripping device adapted to

have one member support said sheaves and pass beneath said cable, and have its other member operated from the car to grip the cable between it and the first member, substantially as and for the purpose set forth.

3. In a cable railway, one or more fixed or stationary cables supported above and distributed as desired in the direction of the length of the road-bed, combined with one or more sheaves supported below the car and adapted to pass under said cable, and with a gripping device to clamp the cable to said sheave, to thereby stop the motion of the car, substantially as described.

4. A fixed or stationary cable and means, substantially as described, to support the same above the road-bed, combined with a gripping device supported by and operating from the car, substantially as and for the purpose specified.

5. A fixed or stationary cable and means, substantially as described, to support the same above the road-bed, combined with a gripping device consisting of a lower jaw adapted to pass beneath the said cable, a sheave or roller rotating in a slot or opening in said lower jaw, and an upper jaw adapted to be moved from the car to grip the cable between it and the lower jaw, substantially as described.

6. A fixed or stationary cable and means, substantially as described, to support the same above the road-bed, combined with a gripping device consisting of a lower jaw provided with corrugations or teeth and adapted to pass beneath the said cable, a sheave rotating in a slot or opening in said lower jaw, and an upper jaw provided with corrugations or teeth, and adapted to be moved from the car to grip the cable, as and for the purpose specified.

In testimony whereof I have signed my name to this specification in the presence of two subscribing witnesses.

LOUIS GODDU.
